CLAIM

The ornamental design for an inflatable water slide and pool,
as shown and described.

DESCRIPTION

FIG. 1 is a perspective view of the inflatable water slide and pool
according to my new design, as seen from the right
front corner thereof.

FIG. 2 is a perspective view of the inflatable water slide and pool,
as seen from the left front corner.

FIG. 3 is a front elevational view thereof.

FIG. 4 is a perspective view of the inflatable water slide and pool,
as seen from the rear; and,

FIG. 5 is a rear elevational view thereof.

The broken line showing of two sleeves for inflation is for
illustrative purposes only and forms no part of the invention.
